DEBURRING OR POLISHING MACHINE

Walter B. Moore, West Lafayette, Ohio

Application December 6, 1952, Serial No. 324,474

9 Claims. (Cl. 51—92)

My invention relates to a deburring or polishing machine. It has to do, more particularly, with a machine for deburring or polishing the interiors of hollow articles of annular cross-section.

My machine is especially suitable for deburring or polishing the interiors of shell casings. These casings have a number of perforations punched inwardly through the side walls thereof which produce burrs, on the interiors of such walls, that must be removed. Because each of the shell casings has a neck which is narrower than the body thereof, it is difficult to insert a proper deburring or polishing tool into the interior thereof and to remove such a tool. In the prior art, deburring tools have been provided which include abrasive members that expand by centrifugal force, created by rotation of the tool, into contact with the wall of the hollow article after being inserted therein. These members are usually retracted by spring or lever retractors to permit removal of the tool from the article. The result is that the devices are complicated, and excessive centrifugal force is required for expanding them into contact with the work.

It is the object of my invention to provide a very simple deburring or polishing machine for use on the interiors of hollow articles which includes a tool head that is contracted before it is inserted into the hollow article, is readily expanded by centrifugal force into contact with the interior of the wall of the hollow article, and is easily contracted and retracted when the deburring or polishing operation is completed.

Although in this description I refer to my machine as being used for operation on the interior of shell casings having narrow necks, it is to be understood that it can be used on other articles with narrow necks, on articles of straight cylindrical form, on tapered or flared articles, and on other hollow articles of annular cross-section.

The preferred embodiment of my invention is illustrated in the accompanying drawings wherein similar characters of reference designate corresponding parts and wherein:

Figure 1 is a plan view, partly broken away, of a machine made according to my invention.

Figure 2 is a vertical sectional view taken substantially along line 2—2 of Figure 1.

Figure 3 is an elevational view, partly broken away, of the end of the machine where the operator will be disposed.

Figure 4 is a transverse sectional view taken substantially along line 4—4 of Figure 2.

Figure 5 is a detail in side elevation, partly broken away, of a tool head of the machine retracted in the associated retracting ring outside the hollow article.

Figure 6 is a transverse sectional view taken substantially along line 6—6 of Figure 5.

Figure 7 is a view similar to Figure 5 but mainly in longitudinal section and showing the tool head in expanded condition within the hollow article.

Figure 8 is a transverse sectional view taken along line 8—8 of Figure 7.

2

Figure 9 is a perspective view of the end of the machine where the tool heads and associated retracting rings are located.

With reference to the drawings, I have illustrated a machine which is designed to hold two shell casings for the deburring or polishing operation. However, it is to be understood that the machine may be designed to hold any number of articles and that these articles may be hollow articles of different types.

The machine includes a base plate 10 which is suitably supported in horizontal position by a supporting frame

11. Upon the base plate 10 is movably mounted a carriage 12 adapted to carry the shell casings S. The tool heads 13 and the actuating units 14 therefor are disposed above this plate 10 in association with the carriage 12.

The carriage 12 comprises a rear vertically disposed plate 15 extending transversely and welded to the longitudinally extending side bars 16. The forward ends of the side bars 16 are welded to a transversely disposed vertical fixture plate 17 which has transversely spaced cradling notches 18 formed therein for receiving the reduced necks N (Figure 9) at the open ends of the shell casings S. Disposed between the bars 16 and welded thereto at the rear of the carriage is a vertically disposed transverse fixture plate 19 which is spaced slightly ahead of the plate 15 and is parallel thereto. This plate 19 is provided with cradling notches 20 in axial alignment with the notches 18 and for receiving the rear ends of the shell casings S. Each of the casings S is provided with a flange F (Figure 2) at its closed end which will be positioned

between the plates 15 and 19 and will prevent axial movement of the shells forwardly on the carriage or to the right of the carriage with reference to Figure 2. The shells will be positioned in the carriage from the top side which will be open. They will merely be dropped into the aligning cradling notches 18 and 20, the lower halves of the flanges F being disposed between the two plates 15 and 19 around the semicircular lower portions of the cradling notches 20.

For holding the shell casings S in fixed position within the cradling notches 18 and 20 and to prevent rotation thereof during the deburring operation, locking levers 21 are provided at the rear end of the carriage 12. These locking levers 21 are pivoted at 22 to the vertical plate 15 and are provided with beveled and shouldered upper ends 23 which are movable through slots in the plate 15 and are adapted to engage the flanges F at the uppermost points thereof. The manner in which these locking levers 21 are operated will be described later. Normally they are not in engagement with the flanges F and are so positioned as to permit dropping of the shell casings S into their cradling notches 18 and 20 or lifting of the shell casings therefrom.

The carriage 12 is carried by four rollers 30 which are supported on transverse shafts 31 that are attached to the lower side of the carriage. These rollers operate on angle members 33 which extend longitudinally of the base plate 10 in parallel relationship and are supported thereby. Guide angles 32 are secured to the angle members 33 and extend over such angles. Thus, the angle members 32 and 33 will guide the carriage 12 in its longitudinal reciprocations on the base plate 10 which reciprocation will be necessary, as will later appear, to operate the machine. Vertically disposed guard plates 16a are provided along each side edge of the base plate 10 and have their lower edges secured to the angles 33. These plates extend half the length of the base plate 10 and when the carriage 12 is in its normal position, shown in Figure 1, the plates 16a lie along each side of the carriage.

The vertical plate 15 at the rear end of the carriage has supported thereon latching means for holding the

carriage in its rearwardmost or left hand position (Figure 2) and means for actuating the locking levers 21. This mechanism is shown best in Figures 2 and 3. It includes a handle member 35 which is supported by upstanding angles 36 which are secured to the plate 15 and the side bars 16, the handle 35 being held in rigid fixed position. The handle member 35 carries a pair of depending pins 37 upon which is slidably mounted a second handle member 38. This handle member 38 is normally held in its lowermost position by means of compression springs 39 disposed between the members 35 and 38 on the pins 37. The handle member 38, in turn, is provided with a pair of depending bolts 40 which carry a transverse bar 41, parallel to handle 38, at the lower ends thereof. Midway between the ends of the bar 41, a latch member 42 is mounted for vertical movement, being normally retained in its lowermost position by means of a compression spring 43 which engages at its lower end a shoulder on the lower end of the latch and at its upper end engages the bar 41. This latch member normally extends downwardly behind a keeper 44 which is secured to the base plate 10. It will be noted from Figure 2, that the latching levers 21 are pivoted off center and normally swing downwardly and forwardly into engagement with the transverse bar 41.

When it is desired to move the carriage 12, the handles 35 and 38 are gripped with the hands and the handle 38 is pulled upwardly against the force of the springs 39. This will exert an upward pull on the transverse bar 41. Consequently, the latch member 42 will be pulled upwardly and will be released from the keeper 44 so that it will now be possible to push the carriage 12 forwardly on the base plate 10. Upward movement of the bar 41, also causes the upper ends of the locking levers 21 to swing forwardly and engage the flanges F of the shell casings S at their uppermost points. This will serve to prevent rotation of the shell casings in the cradling notches 18 and 20. When operation on the shell casings is completed, the handle 38 may be released and this will release the locking levers 21 since springs 39 will push the bar 38 downwardly and will, therefore, lower the bar 41. The carriage may now be moved rearwardly to its original position, the lower end of the latch member 42 merely sliding along the base plate 10 until it reaches the keeper 44, when the cam surface 45 of the latch member will ride up over the keeper, permitting the latch to snap behind the keeper and retain the carriage in position until the handle 38 is again moved upwardly.

As indicated previously, the shell casings S are loaded into the carriage 12 through the upper open side thereof and while the carriage is locked in its initial position. The shell casings are removed through the upper open side of the carriage, after the carriage is returned to and is locked in its original position.

The tool heads 13 are carried by suitable units 50 for producing rotation thereof. These units may take various forms but I prefer to use air motors. Each of these units is supported in fixed position by suitable piping as shown provided with a shaft 51 (Figure 1) which carries a tool head 13. Air is supplied to these motors by suitable piping as indicated. The motors are supported rigidly in positions spaced above the base plate 10 and in axial alignment with the shell casings S when they are supported on the carriage 12. A hinged cover 52 of inverted U-form in cross section is provided over this portion of the machine, extending from the vertical side plates 16a to the right hand or forward end of the machine as shown best in Figure 1, being hinged to one side of the plate 10 as shown in Figures 1 and 9 by hinges 53a. An end wall 53 is provided as a guard at the forward end of the machine and is suitably secured at its lower edge to the angle members 33.

The piping for operating the air motors of the units 50 includes a pipe 54 which extends beneath the plate 10 towards the rear end of the machine. This pipe includes a

valve 55 which has an operating plunger 56 that normally extends upwardly through an opening in the base plate 10. The carriage 12 carries at its lower side, directly above the plate 10, a valve actuating strip 57 which is in rigid fixed position on the carriage midway between the sides thereof and in axial alignment with the plunger 56. The forward end of the strip 57 is provided with a beveled or cam portion 58.

Normally with the carriage 12 in its initial position at the rear end of plate 10, the forward end of strip 57 is spaced rearwardly from the valve plunger 56, as shown in Figure 2. Therefore, the valve is normally closed. As soon as the carriage, however, is pushed forwardly, the plunger 56 is engaged by the strip 57 and is pushed downwardly so as to open the valve 55. This will supply air to the units 50 and cause the tool heads 13 to rotate.

The tool heads 13 are illustrated best in Figures 5 to 8. It will be noted that the end of each shaft 51, which is driven by a unit 50, is provided with a disc-like portion 60. Pivoted to this disc 60 by means of the pivot bolts 61 are the abrasive fingers or levers 62. These levers 62 have outer ends 63 of a curvature corresponding to that of the interior of the shell casings. The fingers 62 are arranged in a single pair and extend in opposite directions from diametrically opposed points so that their opposed ends will swing outwardly away from each other upon rotation of the tool unit. If desired, the members 62 may carry replaceable abrasive pads or other selected working members on their outer ends. It will be apparent that the centrifugal force created by rotation of the shaft 51 will swing the fingers 62 outwardly.

It will be understood that when the carriage 12 is first moved to the right (Figures 1 and 2) the tool heads 13 will not yet be rotating. They will, however, be positioned in the retracting rings 64. These rings are formed in blocks which are removably secured by bolts 65 (Figure 7) in flanges 66 attached to the fixture plate 17. Obviously, the rings 64 will be in axial alignment with the shell casings S supported by fixture plates 17 and 19 and with the tool heads 13 carried by the shafts 51. With the carriage 12 in its initial position where it is locked at the left or rearward end of plate 10, the tool heads 13 will be positioned as shown in Figures 5 and 6, so that the finger 62 will be retracted within the rings 64.

As soon as the carriage 12 is moved to the right, the rings 64 will move therewith towards the right and as soon as the tool heads move out of the rings 64 and into the shell casings S, the centrifugal force created by the rotation of the shafts 51 will cause the fingers 62 to swing outwardly into engagement with the inner wall surface of the shell casings. Proper contact will be made by centrifugal force throughout the necks and the bodies of the shell casings and the flared connecting portions thereof. As previously indicated, rotation of the shafts 51 will begin as soon as the operating strip 57 on the carriage 12 engages the valve plunger 56. This will be just at the instant that the tool heads 13 enter the open ends of the shell casings.

The carriage 12 may be moved slowly to the right at such a speed that the deburring or polishing operation will be performed properly and the entire inner surface of each shell casing S will be contacted by the ends of members 62. As soon as the full length of the shell casings is traversed, the carriage 12 will be pulled back to its original position. As it nears the end of its return movement, the rings 64 will move over the tool heads 13. It will be noted from Figures 5 and 7, that the rings 64 each have a beveled surface 67 at the side adjacent the mouth of the shell casing. This surface will form a beveled mouth which at its outer side is of substantially the same diameter as the neck N, the diameter of the main opening in the ring 64 being slightly smaller than that of the neck. Therefore, as the carriage 12 nears the extent of its movement to the left, the tool heads 13 enter the rings 64 and the beveled surfaces 67 will gradually re-

tract the finger 62 so that they can move completely within the rings. The heads will now be ready for insertion into the mouths of other shell casings. The rings 64 will be supported close to, but slightly spaced from, the ends of the shell casings S (Figures 5 and 7) so as not to interfere with rotation thereof. However, the fingers 62 will be sufficiently wide, as shown in Figure 5, to bridge this space. With the carriage 12 locked in its initial position, the shell casings S will be positioned relative to the rings 64 as in Figure 5 and can be readily lifted from the cradling notches 18 and 20 of the carriage. The flared mouth 67 of the ring 64 will face the open end of the shell casing S and will be of a diameter at least that of the open end of the casing but the main part of the ring will be of slightly less diameter as indicated above. This will ensure that the tool head will be contracted as it leaves the shell casing. Furthermore, this action will be facilitated because the fingers 62 will bridge the space between the open end of the article and the flared mouth of the ring.

It will be apparent from the above description that I have provided a machine which performs its operations automatically upon movement of the carriage along the supporting base. The tool heads are of such a nature that centrifugal force will readily move the tool members into contact with the walls of the casings. The retracting rings provide simple means for automatically retracting the tool members as they leave the shell casings and since all springs are eliminated, there is no spring pressure to overcome by the centrifugal force. The use of the air motors for driving the tool heads is preferred since this will allow some yielding to back-pressure developed by the tool head when the working fingers or tool members encounter the burrs.

Various other advantages will be apparent.

Having thus described my invention what I claim is:

1. A machine for operating on the interior of a hollow article of annular cross-section which has an open end to perform a selected operation on the interior surface thereof, comprising a tool head, means for supporting the article, means for supporting the tool head, said tool head including tool members expandible by centrifugal force, means for rotating the tool head, said means for supporting the article comprising a carriage having means for carrying the article, means for reciprocating the carriage, a retracting ring supported on the carriage so that it will be in axial alignment with the open end of the article when supported on the article carrying means on the carriage, said retracting ring having a flared mouth facing the article carrying means, said means for supporting said tool head supporting it independently of the carriage and for rotation in axial alignment with said ring but in fixed position longitudinally so that as the carriage is reciprocated the ring and the article supported by the carriage will be moved axially of the tool head, and means for normally locking the carriage in such a position that the tool head is disposed within the main part of the retracting ring.

2. A machine according to claim 1 wherein said locking

means comprises a latch carried by the carriage and engaging a support on which the carriage is mounted, and means on the carriage for releasing said latch.

3. A machine according to claim 2 wherein said tool head is mounted on a rotatable shaft carried by said support in axially fixed position, said rotating means for the tool head comprising a driving unit for driving said shaft, and means for actuating said driving unit when said latch is released and said carriage is initially moved.

4. A machine according to claim 3 wherein said driving unit comprises a fluid motor, a starting valve connected thereto, said actuating means comprising a cam carried by the carriage and out of engagement with the carriage locked but movable into engagement with said valve upon the initial movement of the carriage.

5. A machine according to claim 4 wherein said carriage is provided with cradling fixtures for holding the article, and means for locking the article in such fixtures to prevent rotation thereof.

20 6. A machine according to claim 5 wherein said locking means comprises a locking lever, and means for moving said locking lever into locking position upon release of said carriage latching means.

7. A machine according to claim 6 wherein said cradling fixtures comprise vertically disposed transverse plates which are spaced longitudinally of the carriage and have aligning cradling notches, one end of the article being closed and having a flange, and an additional plate mounted in slightly spaced relationship to the fixture plate which receives the closed end of the article so that the flange will be disposed between such plates when the article is supported in the fixture plates, said locking lever being pivoted to said additional plate so that it will engage the flange of said article when actuated.

35 8. A machine according to claim 7 comprising a fixed handle on the carriage for moving the carriage, and a movable handle mounted adjacent the fixed handle and movable to release said latching means and actuate said locking lever.

40 9. A machine according to claim 8 wherein the fixture plates are provided with a plurality of sets of aligning notches for receiving a plurality of articles, a corresponding number of locking levers, a corresponding number of retracting rings on the carriage in axial alignment with the sets of notches, and a corresponding number of tool heads in axial alignment with said retracting rings.
